ABSTRACT OF THE DISCLOSURE

Elongated clothesline cleats which secure passes of 10 clothesline for a clothes drier. Each cleat consists of two elongated members which have lateral interpolating projections which extend longitudinally with the members. The clothesline is cooperatively gripped by and between these projections through reverse curvature to prevent it from being withdrawn laterally. U-shaped channels are received over the interengaged cleat with the side flanges of the channel extending therebeyond to provide overlying top and bottom plates. These plates have vertically misaligned openings to receive elongated ground supports in an outwardly disposed manner.

This invention relates generally to clothes dryers and more particularly to an improved portable clothes drier which is easily assembled and disassembled.

The principal object of this invention is the provision of a portable clothes drier which is economical to manufacture and assemble. The clothes drier of the present invention is an improvement over my patent application Ser. No. 495,582, which was filed Oct. 13, 1965, now U.S. Patent 3,335,873, granted Aug. 15, 1967. The present invention has fewer parts to manufacture and requires less labor to assemble the same.

Another object of the present invention is to provide a portable clothes drier with spaced elongated clothesline or flexible material cleats which have elongated members each having laterally interprojecting or interpolating projections with cross-sectional configurations which when receiving the clothesline therebetween cooperatively grip the same through reverse curvature to interlock the flexible material or clothesline preventing it from being withdrawn laterally from between the interlocked cleat. Two advantages are apparent in the structure of this cleat. First of all, no labor is expended in threading each pass of clothesline through holes in the spaced clothesline cleat members and then tying a knot thereafter in the end of the line to prevent it from slipping back through the hole. All the passes of clothesline between the cleats are simultaneously laid across one of the cooperative members and the second cooperative member is then simply interlocked into the first thereby securing all the lines at once. The other important advantage is that the cooperative members making up each clothesline cleat may be identical in structure thereby requiring one common stock type of cooperative member to make up the flexible material or clothesline cleat. This cleat is primarily intended to be used in connection with my portable clothesline rack of the present invention, however, it also has probable application in folding furniture where flexible material such as a light canvas is used.

Another object of the present invention is to provide a clothes drier with spreading means to maintain the elongated clothesline cleats in spaced relation and to keep the lines taut. This spreader means may be in the form of a threadably extendable member placed between the cleats or it may be a novel hinged member of the present invention connected between the elongated cleats which when opened and forced past its dead center position with the lines taut, it will lock itself thereby maintaining the passes of clothesline in a taut condition.

2

A third spreading means and novel feature of the present invention which may be employed, provides a spring loaded member wherein a lever arm is employed to draw two horizontally aligned arm members toward each other thereby compressing a spring disposed between the arm members. In this manner the spreading means may be inserted between the clothesline cleats. When the lever arm is released, the compression spring will longitudinally separate the arm members and maintain the passes of clothesline under tension.

Another object is to provide a portable clothes drier which has spaced parallel overlying sets of top and bottom plates mounted on and extending horizontally from the spaced clothesline cleat members and having an opening in one of the top plates and a corresponding vertically misaligned opening in the respective underlying bottom plate to receive an end of one of the ground supports. The hole in the underlying bottom plate is misaligned with the hole in the top plate so that when the ground support, which may be for example an aluminum tube, is inserted through the holes, it is supported in an outwardly disposed manner so that when a multiple of such supports is employed, the clothesline drier does not have a tendency to tip. Each support leg, being at an angle slightly off vertical, binds in its respective top and bottom holes due to its own weight and thereby tends to be prevented from sliding out. Each set of the spaced top and bottom plates may be formed by the side flanges of a C-shaped channel which is placed over elongated clothesline cleats with its flanges extending therebeyond. The portions of the flanges extending beyond the elongated cleat then form the top and bottom plates in which the misaligned holes are placed to receive one or more of the leg supports. Four such channels may be provided, one at each end of the clothesline cleats or only two need be provided, one at the center of each cleat rail or member. In the latter instance the top extending part of the top flange is provided with two narrowly spaced holes closely adjacent the cleat member encased by the C-channel and the bottom extending flange is provided with two holes which are spaced farther apart and spaced farther from the cleat member than the two top holes. Thus, when a leg or ground support is placed in one of the corresponding sets of top and bottom holes and a second leg is placed 40 in the second set of top and bottom holes, the two legs will normally meet at an apex thereby forcing each leg to bind in its respective set of holes. These holes may be slightly oblong if the legs are tubular or slightly rectangular if the legs are square so that they fit their respective top and bottom holes snugly when entering them at an outwardly disposed angle which is slightly off vertical.

Another object of the present invention is to provide the leg supports with stop means near their ends to be received by the openings in the top and bottom plates thereby preventing them from sliding all the way through their respective openings. This object may be accomplished by tapering the ends of the ground support so that they gradually bind with the openings as they are progressively inserted. This may also be accomplished by providing an abutment surface or edge near the end of the ground support which will engage the bottom plate when the support has been properly inserted in its respective openings.

A more specific object of the present invention is to provide a locking means to lock the supports or legs of the portable clothes drier in place. This locking means may be in the form of a wedge of elastomer such as rubber which when pivoted about an axis as by a small lever arm shaft it will engage the ground support.

Another object of the present invention is to provide the legs or ground supports with anchor means at their

ends which contact the ground. This anchor means may be in the form of a bent spike secured to the end of the support or leg and which may be driven into the ground as by one's heel or it may be in the form of an upwardly facing dish connected by a stem to the leg. In the latter instance sand or other material may be placed in the dish to weight it down if so desired. However, it is not always necessary to anchor the legs down as the length and outwardly disposed placement of the legs is great enough to make tipping of the drier difficult.

Another object is to provide the C-shaped channels with slots along the center of each of their webs to receive the ends of the spreader means which ends may also continue to penetrate into the elongated cleat between successive passes of line where the line enters into the cleat between its interlocking cooperative members. These C-channels also serve as clamps to maintain the cooperative members in interlocking engagement. Where such additional clamps are necessary, other C-clamp channels may be provided along the clothesline cleats. However, the latter cleats need not have their flanges extend beyond the thickness of the cleat and the inside surfaces of the cleat may be provided with inwardly protruding stop abutments to maintain the cooperating members of the elongated cleat in clamped engagement.

Other objects and advantages appear hereinafter in the following description and claims and in the accompanying drawings.

The accompanying drawings show for the purpose of exemplification without limiting the invention or claims thereto, certain practical embodiments illustrating the principles of this invention wherein:

FIG. 1 is a plan view of a clothes drier of the present invention with portions thereof removed for the sake of clarity.

FIG. 2a is an enlarged sectional view in side elevation of the clothes drier shown in FIG. 1 as seen along line 2a—2a.

FIG. 2b is an enlarged end view of the clothesline cleat shown in the clothes drier of FIG. 2a.

FIG. 3 is a plan view of a structural variation of the spreader means employed in the clothes drier of the present invention.

FIG. 4 is an end view of the clothes drier shown in FIG. 1 and illustrates in addition the employment of anchor means.

Referring to FIGS. 1 and 2, the clothes drier 1 is made up of the elongated clothesline member or cleats 2 which receive passes of the clothesline 3. The spreading means 4 is inserted between the cleats 2 to maintain them in their spaced relation thereby maintaining the clothesline passes 3 in a taut position.

The spreading means 4 consists of the arm members 5 which are preferably aluminum tubing and of equal length. The arm members 5 are pivotally secured within the channel 6 by means of the bolts 7 which pass through the openings 9 in the side flanges 10 of the channel 6 and are secured by the lock nuts 8.

The channel 6 is provided with the top opening 11 in order to permit clearance of the ends 12 of the arm members 5 when they are pivoted downwardly about the bolts 7 as illustrated in FIG. 2a when the clothes drier is in its fully extended position. The channel 6 is positioned slightly below the horizontal line of the clothesline 3. The channel 6 is prevented from assuming a lower position by reason of the arm members 5 engaging the ends 13 of the web 14 of the channel. Thus, when the arm members 5 are in their closed position (not shown) such that they lie parallel to each other in a vertical plane, they must be pivoted upwardly and outwardly until the passes of clothesline 3 are in the same horizontal plane as the spreading means 4 at which time the passes of clothesline 3 are in an overstretched condition. The arm members 5 may then be pivoted upwardly past dead center until they maintain the fully extended position illus-

trated in FIG. 2 at which point the clothesline passes 3 are in a taut condition but are, however, somewhat relaxed from their overstretched condition. In this taut condition the passes of clothesline 3 maintain the spreader means 4 in a locked condition.

As the clothesline ages and is repeatedly stretched, it may become necessary to adjust the length of the spreader means 4 in order to maintain the clothesline passes 3 under the desired tension. This is accomplished by providing 10 the multiple adjustment holes 9 in the side flanges 10 of the channel. Thus, the bolts 7 may be removed and the arm members 5 extended outwardly from each other to obtain the desired length at which point the bolts 7 may be reinserted. The adjustment holes 9 are positioned slightly off vertical and in line with the arm members 5 so that as the bolts 7 are re-positioned in the holes 9, the arm members 5 will always maintain the same angular position when the spreading means 4 is placed in its locked or past dead center position.

20 The clothesline cleats 2 consist of the pair of elongated cooperative members 15 which are identical in structure and have the interengaging or interpolating lateral projections 16 which cooperatively grip the clothesline 3 through reverse curvature to interlock the same and prevent it from being withdrawn laterally from between the cooperative members 2. The protruding longitudinal edges of projections 16 are enlarged by longitudinal abutments 18 to maintain the cooperative members in an interlocked or snapped condition when the clothesline 3 is gripped therebetween. The laterally extending projections 16 also extend longitudinally with the elongated members 15.

25 The elongated cooperative members 15 are preferably of extruded aluminum but can also be made from extruded plastic. The interengaging projections 16 grip the clothesline therebetween as the members are pressed together. The spreading means 4 and the cleats 2 are supported above the ground by the legs or ground supports 20 which are preferably a light metal tubing. The supports 20 are secured to the cleats 2 by means of the C-channel 21 which are in clamping engagement with the cleats 2. The channel 21 is also provided with a slot 44 to receive the crimped ends 45 of the spreading means 4.

30 FIG. 2b is a plan view of a structural variation of the spreading means 4. In this figure, the arm members 5 are provided with the top plates 23 and bottom plates 24, respectively. The top plates 23 are provided with the closely spaced openings 25 which are positioned adjacent 35 the clothesline cleats 2. In a similar manner the underlying plate 24 is provided with the vertical misaligned openings 26. The ground supports or legs 20 are slid upwardly into their respective top and bottom misaligned openings as illustrated until stopped by the abutment screws 27. The ground supports are thereby positioned in an outwardly disposed manner making it relatively difficult to tip the clothesline drier.

35 The C-shaped channel 22 not only acts as a clamp to ensure continued engagement of the cooperative members 15 but also serves as a means of connecting the ground supports 20 with the fewest possible parts. The simplicity in the identical cooperative members 15 and in the remaining parts of the drier provides a clothes drier which is economical and provides ease in manufacture and assembly.

40 FIG. 3 illustrates a structural variation of the spreading means 4. In this figure, the arm members 5 are slightly received within the spring housing 28. A lever arm 30 is pivotally connected as shown at 31 to the housing 28 to provide a mechanical advantage in compressing the compression spring 32 disposed between the ends of the members 5. When the lever arm 30 is pivoted about the axis 31 the arm members 5 are drawn toward each other by the compression arms 33 which are pivotally connected between the lever arm 30 and their respective arm

members 5. In this manner the spreading means 4 may be shortened in length and removed or inserted between the clothesline cleats 2.

The spreading means as illustrated in FIG. 3 is advantageous in that mechanical adjustment of the parts is not required from time-to-time as the clothesline progressively stretches after long use.

One of the compression arms 33 may be provided with a slot 34 which permits the lever arm 30 to be positioned parallel with the spreading means 4 when the arm members 5 are extended to the full extent permitted by the cleats 2 and the clothesline 3. This permits one to use the clothes drier without encountering interference by the lever arm 30.

FIG. 4 is an end view of the clothes drier shown in FIGS. 1 and 2 illustrates a locking means 35 which prevents the supports 20 from sliding downwardly out of the openings 25 and 26 when engaged. The locking means consist of the shaft 36 which is bent at one end to provide the handle 37. The shaft 36 is pivotally mounted to the top and bottom plates 23 and 24 and is secured to the resilient wedge 38. When the shaft 36 is pivoted about its axis the wedge 38 engages the legs or supports 20 thereby squeezing them in binding relation with the openings 25 and 26.

The upward extending ends of the ground supports 20 as illustrated in FIG. 4 are provided with a taper which illustrates a structural variation of the abutment screws illustrated in FIG. 1. The top openings 25 in this instance are made slightly smaller than the bottom openings 26 and the supports 20. Thus, when the tapered ends are inserted upwardly into their respective holes, the diameter of the supports 20 gradually increase to binding engagement with the openings 25 thereby providing a locking or abutment means.

FIG. 4 further illustrates two methods of anchoring the clothesline drier to the ground. In the right hand side of the figure, the bottom of the support 20 is provided with the hollow foot 40 which is cemented within the support 20 and receives the bent spike 41 which may be driven into the ground by one's heel. The anchor means illustrated in the left side of the figure is structurally identical except that the spike 41 is replaced with the stem 42 which is provided with a dish 43 at its lower end. The latter anchor means is preferably used in sandy soil where sand or small rocks may be placed in the dish 43 to weight the clothes drier down, when found necessary.

Referring again to FIG. 2b, the clothesline cleats 2 may be provided without the longitudinal abutments 18. In this instance it will be desirable to provide more than two C-shaped channels 21 as shown which may be provided with inturned stop abutments on their side flanges in order to clamp the cleats. Even when abutments 18 are employed, it is desirable to provide a multiple of such channels on each cleat 2 to insure this interlocking engagement. The term interlocking is used in the claims in its broadest sense in order to provide claims which read on both structures.

I claim:

1. A portable clothes drier comprising a spaced pair of elongated clothesline members having means to retain passes of clothesline therebetween, spreading means to maintain said members in spaced relation, a pair of elongated ground supports for each member to support said members above the ground, characterized by spaced overlying sets of connected top and bottom plates mounted on and extending horizontally from said members and having an opening in one of said top plates and a corresponding vertically misaligned opening in the respective underlying bottom plate for each of said ground supports to receive the same in an outwardly disposed manner.

2. The portable clothes drier of claim 1 characterized in that said spaced overlying top and bottom plates of each of said sets are the side flanges of a substantially

C-shaped channel in overlying engagement with one of said members with said flanges extending therebeyond to provide said spaced plates.

3. The portable clothes drier of claim 1 characterized by resilient locking means mounted on said plates to engage and lock said supports.

4. The portable clothes drier of claim 1 characterized by anchor means secured to the ground end of at least one of said ground supports to anchor the same to the ground.

5. The portable clothes drier of claim 4 characterized in that said anchor means is a bent spike which may be driven into the ground by one's heel.

6. The portable clothes drier of claim 4 characterized in that said anchor means is a dish having a stem connecting said dish to said support.

7. A portable clothesline rack comprising spaced elongated clothesline cleats securing passes of clothesline therebetween and each having identical elongated members with laterally extending projections which interpolate to cooperatively grip the clothesline therebetween through reverse curvature, C-shaped channels in clamping engagement with said cleats, and spreading means mounted between said cleats to maintain them in spaced relation.

8. The portable clothesline rack of claim 7, said spreading means consisting of a pair of elongated arm members each having one end pivotally secured adjacent each other within and to the side flanges of a U-shaped channel, the other ends of said elongated members engaging said spaced cleats.

9. The portable clothesline rack of claim 7, said spreading means consisting of a pair of arm members each having an end in slidable engagement with a spring housing, a compression spring disposed between said ends, a lever

35 arm pivotally secured to said housing, a pair of compression arms having one end of each pivotally secured to said lever arm on opposite sides of the pivotal connection of said lever arm to said housing and having one of their free ends pivotally secured to one of said arm members and said other free end pivotally secured to the other of said arm members to compress said spring when said lever arm is turned about its pivotal connection to said housing.

10. The clothes drier of claim 9, one of said compression arms characterized by a slot in slidable engagement with its pivot connection to said arm member.

11. The portable clothes drier of claim 7, a selected number of said C-shaped channels having their sides extending horizontally with the passes of clothesline beyond said cleats to form top and bottom plates each having an opening vertically misaligned with the other to receive an end of an elongated ground support member in an off vertical outwardly disposed manner, and locking means to secure said end to said plates.

55 12. A flexible material cleat comprising a pair of parallel elongated members having lateral projections which extend longitudinally therewith and interpolate to cooperatively grip the material therebetween through reverse curvature and prevent it from being withdrawn laterally from between said members.

13. The interlocking flexible material cleat of claim 12 characterized in that said members are structurally identical.

60 14. The interlocking flexible material cleat of claim 12 characterized by means to secure said cooperative elongated members together with the flexible material gripped therebetween.

15. The interlocking flexible material cleat of claim 14 characterized by at least one substantially C-shaped channel in clamping engagement over said elongated members to provide said securing means.

70 16. The flexible material cleat of claim 12 characterized in that the protruding longitudinal edge of each of said lateral projections is enlarged to interlock said members together when said material is received therebetween.

17. The flexible material cleat of claim 16 characterized in that said cooperative members are structurally identical.
